UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

SEWING-MACHINE.

1,188,388.

Specification of Letters Patent. Patented June 27, 1916.

Application filed February 10, 1913. Serial No. 747,414.

To all whom it may concern:

Be it known that I, ARTHUR BATES, a subject of the King of England, residing at Leicester, Leicestershire, England, have invented certain Improvements in Sewing-Machines, of which the following description, in connection with the accompanying drawings, is a specification, like reference characters on the drawings indicating like parts in the several figures.

This invention relates to machines used in the manufacture of boots and shoes and more particularly to that type of machine in which a curved needle is provided to effect the permanent stitching together of the sole and upper of turn shoes. An example of a sewing machine of this type is what is known in the trade as the Goodyear welt and turn shoe sewing machine and the stitch-forming devices of this machine are applicable with particular advantage to machines constructed in accordance with the present invention.

The object of the present invention is the provision of a sewing machine of the above general type but which is so organized as to be capable of sewing an unlasted shoe upper permanently to a sole and which is adapted to be of very advantageous use in connection with turn shoes having soles of flexible material (such as felt).

Felt soled shoes as now made generally comprise a textile fabric upper and a felt sole, and these parts have been heretofore sewn together by hand without any preparatory lasting process, the handcraftsman lasting or manipulating the upper and sole as he or she stitches them together so as to insure the correct relationship of the two parts. By the use of a machine constructed according to this invention shoes of this kind have their unlasted uppers and soles, without the use of a last, manipulated into a correct relationship of their adjacent edges and permanently sewn together at a single operation.

A feature of the present invention is the provision of a machine for securing an unlasted shoe upper, *i. e.*, an upper off the last, permanently to a sole and characterized by a rotary or other horn adapted to support one face of successive portions of the sole margin (the sole and upper being outside in,

if the work be a turn shoe) and a member that coöperates with the horn to hold the marginal portion of the upper against the other face of the sole and in such relationship to a preferably work-feeding or other curved needle that the barbed point of the said needle will pierce through both the margin of the upper and that surface only of the sole that is adjacent thereto to permanently stitch them together.

The member coöperating with the horn may consist of a presser foot, and according to another feature of the invention, which may or may not be employed, the said foot may be so formed as to co-act with a corresponding part on the horn to cause a portion of the shoe bottom to be raised locally opposite the curved needle so that the needle may penetrate both upper and sole without making too broad a seam. Conveniently, this presser foot may be of claw-like or bifurcated formation so as to engage the work at points displaced at each side of the point where the end of the horn engages it, and the said end of the horn may be formed or provided with a projection or button so that when the work is pressed between the presser foot and the horn a ridge, mound or projection in the work will be produced through which the needle can enter and then emerge near the point of entrance.

In accordance with a further feature of this machine the arrangement of the horn and its coöperating member or presser foot is such that they are separated to permit the feed of the work. In the preferred construction the horn is operatively connected with the presser foot and so correlated that when the horn is depressed the presser foot is lifted. This arrangement provides that the work shall be freed more quickly and thoroughly for the purpose of feeding, and for enabling a more ready manipulation of the upper and sole into correct relationship than is the case when the presser foot alone is moved.

I have herein shown novel features of invention concerned with the actuation of the presser foot and the horn which have been devised jointly by me and Alfred Richards and are therefore being claimed in another application filed February 13, 1913, Serial No. 748,148.

These and other features of the invention will now be described as embodied in the illustrated machine. It is to be understood, however, that this embodiment is by 5 way of illustration merely and not by way of limitation, since the invention could be embodied in other forms and the construction, disposition and operation of the parts could be varied without departing from the 10 spirit thereof.

In the said drawings: Figure 1 is a side view of the machine with parts in section, of sufficient of the stitch-forming mechanism of the well-known type of Goodyear 15 sewing machine to enable the invention to be understood; Fig. 2 is a detail plan of the shoe-engaging devices; and Fig. 3 is an enlarged view of the parts closely adjacent to the shoe.

20 In the illustrated construction the sewing machine comprises a head 2 that supports the usual stitch-forming devices including a curved needle 3 and a looper 4 located above a curved horn 5 upon which the work 25 is supported for the sewing operation.

The horn is shaped to enter a shoe and is mounted, preferably so as to be capable of rotation, to bring different parts of the shoe into operative relationship with the 30 sewing devices. Further, the horn is adapted to be depressed by connection with a treadle for the reception and removal of work and, as will appear later herein, is automatically depressed to a lesser extent 35 to enable the work to be fed. To this end the horn 5 is provided with a sleeve 6 that is received within a bore in a bracket 7 projecting from the base of the head 2 and surrounds a supporting spindle 8 upon 40 which it is capable of being rotated, for which purpose a ball bearing 9 is provided between the lower end of the sleeve 6 and an enlargement 10 of the spindle 8. Relative vertical movement between the spindle 45 and the sleeve is prevented by the boss 11 of an arm 12 fixed to the spindle 8 by a bolt 13, this boss engaging in a recess in the upper end of the sleeve. The sleeve 6 is of sufficient length to permit of an up 50 and down motion in the bracket 7 and is raised and lowered by a toggle 14, 15 the upper end of the link 14 being connected with the spindle 8 at 16 while the lower link 15 is centered at 17 in the bracket 7 55 and is in the form of a bell-crank lever the outwardly extending arm 18 of which is connected with a treadle rod 20. A screw 21 threaded through the frame forms an abutment for the central joint of the toggle 60 and acts as an adjustable stop to regulate the height to which the horn will be raised, this raising being accomplished by a spring 19 that connects the arm 18 of the bell-crank lever with the frame and tends to 65 maintain the toggle straightened. The

screw 21 is provided with a lock nut 22 to maintain it in the position to which it has been adjusted.

From the foregoing it will be understood that the curved horn 5 is normally held in 70 raised position, which is variable according to circumstances, by the spring 19 but that it can be lowered for the removal, insertion or manipulation of the work by the "breaking" of the toggle by lowering the rod 20 75 through the operation of a treadle to which the rod is connected.

The horn is curved as aforesaid so as to extend within the shoe and is provided at its upper end with a projecting button 25 80 that forms a support for the shoe sole. In the present construction the button is circular in plan and its upper surface is of spherical formation so as to raise a portion of the shoe bottom into a mound. Cooper- 85 operating with the projecting button 25 is a presser foot or clamping device 26 which is bifurcated, as shown in Fig. 2, to form fingers 27, 28, arched in a vertical plane, and which, by engaging the work, serve to 90 press the upper and sole together and to deform the sole so as to provide a projection through which the curved needle 3 can penetrate. The claw 27 under which the work first passes preferably is beveled 95 in order to avoid marring the work and also to assist the passing of the work under it when manipulated by the operator; and it may, if desired, be shorter than its companion 28.

100 The presser foot 26 is pivoted at 29 to the upstanding ears 30 of a bracket 31 (see Fig. 2) secured to a projecting portion 32 of the head 2. An edge gage 33 for positioning the work is provided, and the flat shank portion 34 of this gage extends under the bracket 31, being adjustably secured thereto by a thumb-screw 35 which passes through a slot in the portion 34 and screws into the said bracket. Extending under the 110 presser foot is an enlargement 36 formed on the front of the shank portion 34 of the gage, this enlargement serving as a means for determining the distance between the line of stitches and the edge of the work 115 and also assisting in positioning the upper in the desired relation to the sole immediately before the upper is secured thereto. That side of the enlargement 36 which first engages the work, *i. e.*, the right-hand side 120 as viewed by the operator, is formed with an upstanding lip 37 that abuts against the leading side of the presser foot, while another projection 38 extends upward between the fingers 27, 28, as shown in Fig. 2.

125 It is to be understood that in the use of the machine constructed according to this invention for the manufacture of felt soled turn shoes the edge of the upper overlaps the edge of the sole and in this position they 130

are presented to the machine to be sewn and are afterward turned inside out. In this embodiment of the invention the work is fed by the needle 3 which is of the curved type that in penetrating moves in the arc of a circle. For thus feeding the work the needle carrying lever 42 is mounted on a bracket 43 depending from a slider 44 that is adapted to be moved horizontally toward the left-hand side of the machine after the needle has penetrated the work to feed the work, suitable mechanism being provided to accomplish this movement. To allow the feeding movement of the work by the needle the horn is lowered and this is effected by connections between the needle-actuating mechanism and the horn-lowering device. These connections may comprise a link 45 connected at one end to the lever 46 by which the needle is oscillated through its arc and at the other end to an arm 47 loosely mounted at 17 on the stud or spindle on which is mounted the bell-crank lever forming the lower element 15 of the toggle. The lever 46 is pivoted at 48 to the machine frame and carries a cam roll 49 that stands in a groove cut in the side of a cam disk mounted on the main shaft. The movements thus imparted to the lever 46 are communicated to the needle by a link 50 universally jointed at one end to the needle-carrying lever 42 and at the other end to the lever 46. The universal joints permit the lateral movement of the needle to feed the work. The arm 47 has adjustably secured to it, by a screw and slot connection, a plate 51 having a laterally projecting tappet 52 which operates on an extension 53 of the arm 18 of the bell-crank lever 15, 18 and sufficient "lost motion" is provided between the contacting surfaces to provide a lowering of the horn merely sufficient to enable the work to be fed freely. The adjustment of the plate 51 on the arm 47 enables the operator to vary at will the extent to which the horn is lowered during the feeding movement. To prevent the treadle rod from being moved while the horn is automatically lowered for the feeding of the work the connection between the treadle rod 20 and the arm 18 of the bell-crank lever is constituted by a pin 54 projecting from the latter that enters a slot 55 in the treadle rod which is normally maintained raised by a spring 56 that connects it with a projection upon the frame. A stud 57 carried by the treadle rod 20 limits its upward movement by contacting with the said projection. In this embodiment of the invention in addition to the horn being lowered the presser foot is raised while the work is fed by the needle, and consequently connections are provided between the presser foot and the horn-lowering device. These connections are arranged as follows:—The aforementioned arm 12 that is secured at one

end to the upper end of the spindle 8 rigidly supports at its other end an upright stud 58. On this stud two collars 59, 60 are pinned at a distance apart, so as to leave a space between them in which is located a block 61 that slides on the stud 58 and that is normally kept in contact with the lower collar 60 by a spring 62 which is disposed between the block 61 and the upper collar 59. The block 61 is connected by a link 63 with the rear end of the presser foot 26.

An abutment 65 on the bracket 31 is provided below the rear arm of the presser lever so that when the presser is raised from the work, for the purpose of feeding the rear arm will rest on the abutment and the presser foot will be held stationary clear of the sewing devices, the spring 62 providing for the further downward movement of the horn after the presser foot has been raised. Any suitable device may be provided to enable the height to which the presser foot is lifted to be varied, such for example as a screw threaded through the rear arm of the presser foot and adapted to engage the abutment 65.

The operation of the machine as far as concerns the present invention no doubt will be understood from the foregoing description of the different parts but it may be briefly recapitulated as follows:—The operator depresses the treadle and thereby through the treadle rod 20 and connected bell-crank lever "breaks" the toggle and lowers the horn ready for the reception of the work. After this has been placed upon the horn the treadle is released, the toggle is straightened and the work pressed between the end of the horn and the claw-like end of the presser foot 26, which latter has been depressed through the arm 12, link 63 and other parts connecting the presser foot with the horn. The machine is then started and during the progress of the stitching the work is fed by the transverse movement of the needle, the horn being lowered automatically and the presser foot raised at each stitch through the loosely mounted arm 47 and tappet 52 that comprises part of the connections between the needle-actuating lever 46 and the horn-lowering device.

Having fully described my invention, what I claim as new and desire to secure by Letters Patent of the United States is:

1. A machine for securing an unlaisted shoe upper permanently to a sole off the last having, in combination, a curved needle and operating mechanism therefor, a rotary horn adapted to extend within the shoe and support successive portions of the sole margin, and a member that cooperates with the horn to clamp the marginal portion of the upper against the outer face of the sole and in such relationship to the curved

needle that the barbed point of the said needle will pierce through both the margin of the upper and that surface only of the sole that is adjacent thereto to permanently 5 stitch them together.

2. A machine for securing an unlasted shoe upper permanently to a sole off the last having, in combination, a curved needle and operating mechanism therefor, a horn 10 adapted to extend within the shoe and support successive portions of the sole margin and a member that coöperates with the horn to clamp the marginal portion of the upper against the outer face of the sole and in 15 such relationship to the curved needle that the point of the said needle will pierce through both the margin of the upper and that surface only of the sole that is adjacent thereto to permanently stitch them together, 20 the tip of the horn and the member that coöperates with it being so shaped and actuated as to form on the surface of the work a projection which intersects the path of the needle.

25 3. A machine for securing an unlasted shoe upper permanently to a sole off the last having, in combination, a curved needle and operating mechanism therefor, a horn adapted to extend within the shoe and support 30 successive portions of the sole margin and a member that coöperates with the horn to clamp the marginal portion of the upper against the outer face of the sole and in such relationship to the curved needle 35 that the point of the said needle will pierce through both the margin of the upper and that surface only of the sole that is adjacent thereto to permanently stitch them together, the said member having two curved 40 fingers or limbs and the horn being provided with a convex tip which forces the work between the said fingers or limbs to form the said projection.

4. In a machine for permanently sewing 45 together a shoe upper and its sole, a needle and its operating mechanism, a horn, a clamping foot coöperating therewith to hold the marginal portion of the upper against the top face of the sole for the needle to 50 pierce through both the margin of the upper and that surface only of the sole that is adjacent thereto, said clamping foot having two fingers overlying the horn and between 55 which the needle can move to feed the work, and an edge gage for the work arranged between the fingers and serving to control the line of stitching in the work.

5. In a machine for permanently sewing 60 together a shoe upper and its sole, a needle and its operating mechanism, a horn, a clamping foot coöperating therewith to hold the marginal portion of the upper against the top face of the sole for the needle to 65 pierce through both the margin of the upper and that surface only of the sole that

is adjacent thereto, said clamping foot having two fingers overlying the horn and between which the needle can move to insert the stitch and to feed the work between the horn and said foot, the finger under which 70 the work first passes being beveled on its front end substantially as and for the purpose described.

6. In a machine for permanently sewing together a shoe upper and its sole, a needle 75 and its operating mechanism, a horn, a clamping foot coöperating therewith to hold the marginal portion of the upper against the top face of the sole for the needle to pierce through both the margin of the upper and that surface only of the sole that is adjacent thereto, said clamping foot having two fingers overlying the horn and between 80 which the needle can move to insert the stitch and to feed the work between the horn and said foot, said fingers being arched in a vertical plane extending lengthwise of the fingers and the top of the horn being similarly curved substantially as and for the purpose described. 90

7. In a machine for permanently sewing together a shoe upper and its sole, a needle and its operating mechanism, a horn against which the sole is held for the needle to pierce through both the margin of the upper and that surface only of the sole that is adjacent to the upper, said horn being provided at its upper end with a projecting button having an upper surface of spherical formation that constitutes the support for the sole and 100 assists in bending the sole upwardly out of a plane at the stitching point.

8. In a machine for permanently sewing together a shoe upper and its sole, a needle and its operating mechanism, a horn to extend within the shoe and against which the sole is held for the needle to pierce through both the margin of the upper and the portion of the sole that is adjacent thereto, said horn being provided at its upper end with 110 a projecting button having an upper surface of spherical formation that constitutes the support for the sole and assists in bending the sole upwardly out of a plane at the stitching point, and coöperating means 115 pressing the upper against the top face of the sole adjacent to the horn button and constructed and arranged to depress the work at the needle entering point.

9. In a machine of the class described, the 120 combination with a needle and its operating mechanism of a clamping foot having a fork or slot extending in the direction of the needle movement and a work support having a projecting head shaped and arranged 125 to force a portion of the stock up into the slot in the clamping foot and into position to be pierced by the needle.

10. In a machine of the class described, the combination with a curved needle and 130

its operating mechanism of a clamping foot having an opening through its stock engaging face, and a horn adapted to cause a portion of the shoe bottom to be raised locally into said opening at a point in the path of the curved needle so that the needle may penetrate both the upper and the sole and emerge near the point of entrance.

11. In a machine of the class described, the combination with a curved needle and its operating mechanism including means to actuate the needle to feed the work, of a clamping foot of claw-like formation having the bifurcations extending in the direction of the piercing movement of the needle and separated far enough to allow the needle to feed between them, and a work support formed to press the stock up between the bifurcations and produce a mound or projection in the work through which the needle will enter and then emerge on the same side of the work to produce a narrow seam.

12. In apparatus for relatively positioning and permanently sewing together an unlasted shoe upper and its sole, a needle and its operating mechanism and associated parts to form and set stitches through the margin of the upper and that surface only of the sole that is adjacent thereto, a horn to support the inner side of the sole, and an edge gage to position the sole laterally with relation to the needle path and between which gage and the edge of the sole the upper is positioned across the path of the needle.

13. In apparatus for relatively positioning and permanently sewing together an unlasted shoe upper and its sole, a needle and its operating mechanism and associated parts to form and set stitches through the margin of the upper and that surface only of the sole that is adjacent thereto, a horn to support the inner side of the sole and po-

sition the sole vertically with relation to the path of the needle, an edge gage 33 for the side of the shoe between which and the edge of the sole the marginal portion of the upper extends across the path of the needle, and a presser foot 26 extending across the edge of the upper adapted to limit the projection of the upper above to the path of the needle.

14. In apparatus for permanently sewing together a shoe upper and its sole, a needle and its operating mechanism, means which engage the inner face of the sole and is formed to raise the sole immediately inside the needle entering point relatively to the sole at the needle entering point, and fingers extending lengthwise of the needle movement and arched on their lower sides to depress the stock at either side of the needle and at the needle entering and emerging sides of said portion of the sole raised by the sole supporting means.

15. In an apparatus for permanently sewing together a shoe upper and its sole, a curved needle and its operating mechanism and associated stitch forming and setting parts, combined with a rotary horn arranged to engage the inner side of the sole while permitting movement of the work with relation to the horn and support the work relatively to the path of the curved needle for the sewing operation through the margin of the upper and into and out of the upper face of the sole, substantially as described.

In testimony whereof I have signed my name to this specification in the presence of two subscribing witnesses.

ARTHUR BATES.
